United States Patent Office.

ABRAHAM LAPHAM, OF FARMINGTON, MICHIGAN.

Letters Patent No. 81,513, dated August 25, 1868.

IMPROVEMENT IN FENCE.

The Schedule referred to in these Letters Patent and making part of the same.

TO WHOM IT MAY CONCERN:

Be it known that I, ABRAHAM LAPHAM, of Farmington, in the county of Oakland, and State of Michigan, have invented a new and useful Improvement in Portable Hinged Fences; and I do declare that the following is a true and accurate description thereof, reference being had to the accompanying drawings, and to the letters of reference marked thereon, and being a part of this specification.

Figure 1 is a perspective view of my invention.

Figure 2 is an end view of the same.

The same letters refer to like parts in each figure.

The nature of this invention is so to construct a fence that it can easily be adapted to all inequalities of ground, that will stand firm wherever placed, that is economical in construction, that will avoid the necessity of setting posts, and that can readily be folded up, transported, and set up in a new position when desired.

In order to accomplish this end, I construct a fence, consisting of parallel bars, A, nailed or otherwise fastened to upright bars, B, to which, by means of a pivot, C, bolt-hinge, or other suitable device, are attached, near the top end, the bars or braces D, to the top of which is attached top board, E, of the fence.

By spreading the bottoms of the upright bars B and D, (which are pivoted or hinged as above described,) a firm base is made to sustain the fence in a proper position.

The bars or braces D may be made longer than the bars B whenever desired, and when used in a position very much exposed to wind and danger of being thrown down, may be provided with a stake, F, which may be attached in any suitable manner, and driven into the ground, for the purpose of anchoring the fence, and preventing its dislodgment, from any accidental cause.

The ends of the bars A may be bevelled off alternately to the front and rear, so that when brought together, in setting up the various lengths of fence, a lock will be formed, by means of which additional security and a straight line may be given to the fence.

I do not claim broadly a portable fence, such as is shown in the patent to James M. Clark, November 26, 1867; but

What I claim new, and desire to secure by Letters Patent, is—

The portable fence, consisting of the bars B and D, pivoted together near their top, the bars B, provided with cross-bars A, the ends of which are bevelled, and the bars D, provided with the bars E, similarly bevelled, all constructed, arranged, and operating as herein described.

ABRAHAM LAPHAM.
